TRUSS AND SUSPENSOR

Robert R. Norwood, Mineral Wells, Tex.

Application April 10, 1942, Serial No. 438,363

2 Claims. (CL. 128—158)

Although the obliterative or injection method of treating hernia has come into wide use during the past ten years, a support or truss is quite as essential for a time after an injection as a splint is for a broken bone of the leg: and that statement is particularly true if a large scrotal hernia is under treatment. Broadly considered, the object of this invention is to provide a combined truss and suspensor of novel form and suitable for the retention of such a rupture whilst the injection process is going forward. Specific objects will be pointed out hereinafter, in connection with the description of the structure to which they relate.

A truss maker who abides by what is claimed may incorporate such changes as his skill may dictate, without departing from the spirit of the invention.

In the drawing:

Fig. 1 shows in front elevation a truss constructed in accordance with the invention;

Fig. 2 is a side elevation;

Fig. 3 is a composite perspective showing the pad;

Fig. 4 is a section through the assembled pad.

In the drawing, a pair of pads P is shown, each pad comprising a rigid, elongated front plate 1, generally made of metal, and shown as of rectangular outline. About its periphery, the plate 1 is supplied with a backwardly inclined flange 2, adapted to insure a good marginal hold on a flexible, washable cover 3, which may be made of cotton flannel. The front plate 1 is supplied with a central opening 4, and is provided near its ends with an outer stud 5 and an inner stud 6. Between the opening 4 and the stud 6, the plate 1 has holes 7, disposed in an upwardly slanting line.

The pad P includes a main member 8, corresponding in outline to the front plate 1, but of slightly greater area than the front plate. The main member 8 is made of washable material, such as felt. It binds the cover 3 against the plate 1, about the opening in the cover. The main member 8 has a central opening 9. The main member 8 is bound tightly between the front plate 1 and a back plate 11 having very short, rearwardly extended prongs 12 at its corners.

The numeral 14 marks an auxiliary member of the pad P, preferably made of washable felt and tapered rearwardly, throughout a portion of its thickness. The auxiliary member 14 may be attached in any suitable way, releasably, to the back plate 11. If desired, the auxiliary mem-

ber 14 may be provided with elastic cords 15, in which the corners of the plate 11 are received. The plate 11 is provided with a central opening 16. A securing element, such as a screw 17, passes through the opening 4 of the front plate 1, the central opening 9 of the main member 8, the screw being threaded into the opening 16 of the back plate 11, and entering the auxiliary member 14 of the pad P, the parts being bound 10 tightly together.

The numeral 18 designates a connecting bar or plate, made of rigid material, preferably metal. The bar 18 has a backward slant from its central portion toward its ends. Securing devices 19 connect the end portions of the bar 18 with the front plates 1 of the pads P, the securing devices passing through the openings 7 of the front plate. The pads P have a pronounced upward divergence, and the upper, inner corner portions of the pads are spaced slightly apart.

The letter B serves to designate, generally, a body encircling belt, including a main section 20, preferably made of resilient webbing. At 21 there appears an upper loop, and at 22 a lower loop. The loops 21 and 22 preferably are made of inelastic material and are held at adjusted lengths, and on the forward ends of the main section 20, by buckles 23 or the like. Eyes 24 are mounted in the bends of the loops or ties 21 and 22, and are adapted to be engaged, respectively and releasably, with the studs 5 and 6 of the front plates 1 of the pads P. Loop-shaped hangers 25 are mounted on the main section 20 of the belt B and are adjustable longitudinally thereof, the 25 hangers carrying buckles 26 or the like.

A suspensor is shown at 27 and is provided at its upper edge with a horizontally elongated eye 28, preferably composed of a strip of textile material, stitched to the suspensor 27. The binding 29 of the suspensor 27 forms pockets 30 at the outer edges of the suspensor. The connecting bar 18 passes removably through the eye 28, the ends of the bar being received removably in the pockets 30. It is to be noted that the screws 40 19, which connect the bar 18 to the front plate 1, by way of the holes 7 are exposed at the front of the suspensor 27, it being possible to detach the screws 19 from the front plates 1, the bar being removed from the eye 28 and the pockets 30, 45 for the washing or repair of the suspensor.

The rear ends of crotch straps 31 are connected to the hangers 25 by the buckles 26, the forward ends of the crotch straps being secured to the suspensor. Throughout most of their length, the crotch straps 31 are received in tubu-

lar coverings 32 made of cotton flannel, for example, having their forward ends secured to the rear portion of the suspensory 27.

The pads P have sufficient area to fit over and exert pressure on the inguinal canal throughout its entire length, including both the external and the internal openings.

The pads P are so shaped, located on the bar 18, and carried by the body belt B, that pressure is exerted above the pubic arch and not against it. It is not necessary to exert pressure upon or below the pubic arch. The external opening of the inguinal canal, the internal opening, and the connecting portion, all are above the pubic arch and pressure must be made there. It is injurious to use a pad which presses the spermatic cord and the soft tissue of the body against the hard and fixed pubic arch.

It is not necessary to apply pressure or support where the intestines go down into the scrotum. The internal opening is midway between the anterior superior spine of the ileum and the tuberosity of the pubic arch. There is no doubt about the importance of where to support the rupture. The lesion is not below the pubic arch, and pressure should not be applied upon or below the arch.

Having thus described the invention, what is claimed is:

1. In a rupture retaining device of the class 30 described, a body belt, a pair of elongated pads,

each of which is of sufficient length to extend the full length of the inguinal canal, including both its internal and external openings and the connecting portion therebetween, the innermost 5 parts of the pad being disposed close together, the inner end edges of the pads having a downward divergence to form an open space avoiding pressure upon or below the pubic arch, the upper and lower edges of the pads having an upward divergence, a rigid bar having its end portions slanted backwardly with respect to a point midway between its ends, means for connecting the pads, near their central portions, to the terminal portions of the bar, means for assembling the belt 10 with the pads, and a suspensory, provided near its upper edge and intermediate its ends with an eye, the suspensory having pockets at its outer edges, the bar extending removably through the eye, and having its ends removably mounted in the pocket.

2. A truss pad comprising a front plate, a back plate having backwardly extended prongs, a main pad member bound between the plates, an auxiliary pad member engaging the back plate and entered by the prongs, and a tightening device connecting the plates and passing through the main pad member, the back plate being reversible on the tightening device, to seat the prongs in the main pad member, when the auxiliary pad member is removed.
